CLAIM

The ornamental design for a bottle and pump head assembly, as shown and described.

DESCRIPTION

FIG. 1 is a front left side perspective view showing the new design for bottle and pump head assembly with the pump in a closed position;

FIG. 2 is a front right side perspective view thereof;

FIG. 3 is a rear left side perspective view from underneath thereof;

FIG. 4 is a rear right side perspective view from underneath thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front left side perspective view showing the new design for bottle and pump head assembly with the pump in an open position;

FIG. 12 is a front right side perspective view thereof;

FIG. 13 is a rear left side perspective view from underneath thereof;

FIG. 14 is a rear right side perspective view from underneath thereof;

FIG. 15 is a front view thereof;

FIG. 16 is a rear view thereof;

FIG. 17 is a left side view thereof;

FIG. 18 is a right side view thereof;

FIG. 19 is a top plan view thereof;

FIG. 20 is a bottom plan view thereof;

(Continued)

FIG. 21 is a front left side perspective view showing the new design for pump head assembly with the pump in a closed position, shown with the bottle removed for clarity of disclosure;

FIG. 22 is a front right side perspective view thereof;
FIG. 23 is a rear left side perspective view from underneath thereof;

FIG. 24 is a rear right side perspective view from underneath thereof;

FIG. 25 is a front view thereof;

FIG. 26 is a rear view thereof;

FIG. 27 is a left side view thereof;

FIG. 28 is a right side view thereof;

FIG. 29 is a top plan view thereof;

FIG. 30 is a bottom plan view thereof;

FIG. 31 is a front left side perspective view showing the new design for pump head assembly with the pump in an open position, shown with the bottle removed for clarity of disclosure;

FIG. 32 is a front right side perspective view thereof;
FIG. 33 is a rear left side perspective view from underneath thereof;

FIG. 34 is a rear right side perspective view from underneath thereof;

FIG. 35 is a front view thereof;

FIG. 36 is a rear view thereof;

FIG. 37 is a left side view thereof;

FIG. 38 is a right side view thereof;

FIG. 39 is a top plan view thereof; and,

FIG. 40 is a bottom plan view thereof.

In the drawings, the evenly-spaced broken lines show portions of a bottle and pump head assembly that form no part of the claim; the dash-dot-dash lines represent boundaries of the claimed design and form no part thereof.
